UNITED STATES PATENT OFFICE.

PEREZ B. HOWARD, OF NEWTONVILLE, MASSACHUSETTS.

AVAILABILITY COPY ARCH-SUPPORT.

1,133,965.

Specification of Letters Patent. Patented Mar. 30, 1915.

Application filed January 30, 1914. Serial No. 815,331.

To all whom it may concern:

Be it known that I, PEREZ B. HOWARD, a citizen of the United States, residing at Newtonville, county of Middlesex, Commonwealth of Massachusetts, have invented certain new and useful Improvements in Arch-Supports, of which the following is a specification.

This invention relates to arch supporters and the like for supporting broken arches or preventing the breaking down of weakened arches of the foot. The usual arch supporter so called is a metallic plate made in general form to fit the curvature of the underside of the foot. Such plates are rigid and stiff and either do not permit flexion of the foot or if permitted, such movements are not followed and therefore offer no possibilities of development of the muscles which assist in maintaining the conformation of the normal arch. These devices are furthermore uncomfortable on account of stiffness and are disagreeable to the wearer. It has also been attempted to introduce a form other than a rigid plate, as for example in such devices as have employed ball cushion pads. These features have also been sometimes combined as where a rigid plate has been employed in conjunction with a small cushion to relieve the oppressive nature of the rigidity. All such devices however are open to the objection that they do not support the foot in its various positions, such as standing and walking. Those that assist the arches of the foot in a standing position are a misfit for the different attitudes assumed by the arches during the flexion of the foot in its different movements. The arches of the foot are plural; there being a longitudinal arch and also a transverse arch. This makes of the curvature of the underside of the foot a very complex surface. In order to properly support this complex arch structure it is necessary that the support be self-adjusting as to load. That is the support must at all times conform to the flexion of the foot and meet the distribution of the weight. This means that the support must be of such a nature as to allow for not only the up and down movement of the muscles and joints, sometimes called the hinge motion of the foot, but allow for the side motion and twisting which occurs in walking. Moreover, when the foot is at rest the effec-

tive pressure should be so confined as to exert a lifting effect upward in its directive tendency to support the arch in its correct normal position. The pressure in walking or lifting the feet must be variable, that is it must be capable of shifting to the required place where it will exert its most effective support and protection to the arch. The support should not confine the foot in any one place but should allow free action of all muscles, tendons and joints so that they may regain their normal strength through the freedom of movement and exercise allowed by the device, and finally the support should be something more than a support alone, it should exert a remedial effect which allows the muscles and tendons of the foot to gradually regain their proper supportive power so that the device can in time be discarded.

To the end therefore of providing an instep support which will possess all these features, I have devised my present invention, which in a usual embodiment consists of an elastic fluid container filled either with a liquid or a gas. The container is of substantially the area spanned by the foot arches but extends slightly under the bases of the arches. It is preferably flattened on its lower face to fit the sole of the shoe while its upper surface conforms substantially to the surface area of the arch structure. The contained fluid is freely displaceable in all directions within said container thus exerting complete uniform pressure upon the different parts of the foot under the arch area. Local vacuum is prevented by a flexible longitudinal rib formed on the under wall of the container and displaceable laterally by the downwardly directed foot pressure.

The construction and principle of my invention will be more fully disclosed in the specification which follows.

In the drawings which form a part of that specification I have shown as an illustrative embodiment a support which has not only proven to be highly efficacious in many cases but is in itself a form capable of convenient manufacture on an extended scale. The very nature of the device makes it somewhat difficult of adequate illustration and it has therefore been necessary to treat the invention more or less diagrammatically in the drawings and to develop in the specification those features so indicated.

2

Throughout specification and drawings like reference numerals are correspondingly applied and in these drawings: Figure 1 is a diagram illustrating a part of a sole with lines indicating the areas under the instep 5 upon which the foot does not rest under different conditions of foot flexion. Figs. 2, 10 3 and 4 are diagrams indicating the arch curves on the lines $x-x$, $y-y$ and $z-z$ of Fig. 1. Fig. 5 is a cross section of my support applied within a shoe and under pressure. Fig. 6 is a perspective view of the support removed, and Fig. 7 is a view particularly illustrating the flexible longitudinal 15 rib which prevents local vacuum in the container.

Referring first to Figs. 5, 6 and 7 of the drawings and particularly to Fig. 5; I have indicated at 1 the instep portion of a shoe 20 and at 2 the insole between which and the instep of the foot (indicated by dotted lines) is confined my novel form of instep support. The support is composed of a container or envelop 3 and two layers of protective material 4 laid one on each side thereof and united thereto in any suitable manner as by a coating of adhesive. The envelop 3 is preferably made of rubber and substantially follows the complex sole surface of the foot 30 as presented when the foot is in normal placement. The envelop therefore consists of a continuous integral communicating middle arch portion 5 and anterior arch areas 6. The middle portion 5 supports the longitudinal arch of the plural arch structure of the foot and the anterior portion 6 the transverse arch of the foot. At one side the envelop has a raised portion 7 conforming to the curved line of the middle arch and extending lengthwise of the envelop. From this portion the envelop slopes down and terminates in tapered edge portions 8 adapted to underlie and receive and transmit pressures from any section of arch base compression to any section of arch relief. Beneath the raised portion 7 the under wall of the envelop is formed with an integral flexible rib 9 extending longitudinally of the container and serving to prevent local vacuum 45 therein. The protective layers 4 are formed preferably of pliable leather. They are usually glued to the container one on each side and to each other at their overlapping edges. The envelop is filled with a fluid capable of being freely displaced therein in all directions so as to maintain a complete uniform pressure upon the different parts of the complex sole surface, while not interfering with the essential freedom of action 50 of the foot muscles.

Referring now to Figs. 1 and 4. In these figures I have endeavored to show by the use of diagrams the action of the support under varying degrees of foot flexion. These views 60 are particularly designed to illustrate the

automatic adjustment for load. For the purpose of illustration I have selected three of the numerous positions of foot flexions and plotted out their variations under the different applications of compressive force. 70 These positions are indicated in Fig. 1 and are first, the position of support when the foot is at rest (indicated by the broken line N—N); second the position of support when foot flexion is normal as in standing, (indicated by the dot and dash lines S—S) and third the position of support when foot flexion is greatest as when the heel is raised in walking (indicated by dotted line W—W). In Figs. 2, 3 and 4 this arbitrary 80 designation is carried out in detail for each support position illustrated in Fig. 1. The indicated lines in all the diagrams represent load adjustment. They indicate the adjustments of the foot arches and show how the 85 fluid in the envelop automatically accommodates itself to variations in the line of application and relative distribution of the effective load, *i. e.*, the weight of the person carried by the foot in question. The first of 90 these positions indicated in Fig. 1 by the broken line N—N is approximately that of the supporting arch bases when the foot is at rest and unflexed. In this position the effective pressure of the contained fluid has a 95 considerable lateral distribution and serves to lightly support the general arch system of the foot in its correct normal position. In Fig. 2 I have endeavored to indicate the 100 arch curvature at each of the fore and aft lines $X-X$, $Y-Y$ and $Z-Z$ which intersect the broken line N—N of Fig. 1 which as above explained indicates the line of support for the arches under normal (unloaded) position of the foot. The indicated arch curvature along the line $X-X$ is shown by the broken line $A-A'$, that of $Y-Y$ by the broken line $A'-A''$ and that of $Z-Z$ by the broken line $A''-A'''$. The second of these 105 positions indicated in Fig. 1 by the dot and dash line S—S is that of the support when the foot flexion is normal as in standing. In this position the line of application of the compressive force has been changed from that indicated in Fig. 2 and it now becomes necessary for the support to automatically adjust itself to this new line of application. This the support does by automatically shifting the effective supporting pressure to the place where it is most required. The dot and dash line in Fig. 3 represents the arch curvatures spanning the portions of the area indicated by the dot and dash line S—S in Fig. 1 along the fore and aft lines $X-X$, $Y-Y$ and $Z-Z$ in Fig. 1. The arch curvature for the line S—S taken across $X-X$ is indicated in Fig. 3 by the dot and dash line $C-C'$, that of the line $X-X$ (Fig. 1) by $C'-C''$ and that of $Z-Z$ by $C''-C'''$. The third of these positions, in 110 115 120 125 130

dicated by the dotted line W—W Fig. 1 represents the line of the supporting arch bases when the foot flexion is greatest, as in starting to walk. It is at this time that the greatest freedom of action for the foot muscles is demanded and it is in this respect that the usual types of supports fail since their tendency is to confine the foot in one place. In walking there is an up and down movement of all the muscles of the foot after the manner of a hinge. In addition there is a side motion and a twisting effect produced by the rotative play in turning in on the ball of the foot. These movements naturally produce a very complex surface area to be supported and it is in this position more than in any other that the envelop must accommodate itself to the varying lines of force applied so as to maintain complete uniform pressure upon all parts of the sole under the arch area. In Fig. 4 the dotted curves E—F, E¹—F¹ and E²—F² represent the arch curvature along the lines X—X, Y—Y and Z—Z respectively in Fig. 1 for the supporting areas bordering upon the dotted line W—W, Fig. 1. The actual curvature is of course too complex to illustrate otherwise than diagrammatically by those familiar with the anatomy of the normal foot and with the varying conditions presented in orthopedic problems.

The supporting envelop should conform as nearly as possible to the arch concavity and should underlie at its margin the arch supporting base areas. Each movement of the foot will then be followed by the shifting of the effective depth of fluid to support each portion of the arch by the uniform transmitted pressure.

Various modifications in the form and arrangement of my device may obviously be

resorted to within the limits of the appended claims.

What I therefore claim and desire to secure by Letters Patent is:—

45

1. A flexible arch support comprising a flexible fluid filled cushion having an upper wall shaped to conform to the normal arch of the human foot, and base and side walls connected to said upper wall and forming therewith a closed chamber and serving to hold the upper face in its proper position in the shoe.

2. A flexible arch support comprising a closed flexible container shaped to fit the normal contour of the foot arch, and a fluid in said container freely movable therein, to afford selective support of the arch members.

3. A flexible arch support comprising a flexible envelop, the upper surface of said envelop being shaped to conform to the normal arch of the human foot, a fluid container in said envelop, and means tending to maintain the support against lateral displacement.

4. A flexible arch support comprising a side wall, said side wall being provided with a base wall, a yielding wall adapted to engage and support the arch of the human foot, said yielding wall being connected at one of its edges to the outer edge of said base wall, and at another edge to said side wall, and forming a closed chamber under said yielding wall and a fluid contained in said chamber.

In testimony whereof I affix my signature in presence of two witnesses.
